UNITED STATES PATENT OFFICE.

HENRY MACNAUGHTON MACNAUGHTON-JONES, OF HAMPSTEAD, LONDON, ENGLAND.

ADJUSTABLE SUPPORT OR BRACKET FOR LAMPS, SHADES, MIRRORS, OR THE LIKE.

1,140,051.

Specification of Letters Patent. Patented May 18, 1915.

Application filed August 27, 1914. Serial No. 858,834.

To all whom it may concern:

Be it known that I, HENRY MACNAUGHTON MACNAUGHTON-JONES, subject of the King of Great Britain, residing at 521 Finchley road, Hampstead, London, England, have invented certain new and useful Improvements in Adjustable Supports or Brackets for Lamps, Shades, Mirrors, or the like, and of which the following is a specification.

10 This invention relates to supports or brackets for carrying lamps containing electric or gas lights, or for carrying shades, reflectors or the like, in such manner that the article carried, hereafter in this specification termed a lamp, can be placed in any desired position within the possible range of movement of the carrying device and will be automatically balanced and thereby maintained at rest in whatever position it may be 15 placed, and can be freely moved from one position to another.

The invention, hereafter more fully described, consists of a structure which is adapted to rotate around a supporting pivot, 20 called hereafter the principal pivot. The principal pivot connects the structure to a standard, pendant rod or bracket, so that the structure is rotatable in its own plane. This structure has the lamp and counter- 25 weight attached to it on opposite sides of the principal pivot, which is situated at the center of gravity of the whole. The structure consists of rods or members hinged or pivoted together to form a parallelogram, 30 or series of parallelograms.

If there be more than one parallelogram two of the adjacent sides of each are prolonged to form a cross, and the prolongations form two of the sides of the parallelo- 35 gram next to it.

With such a construction the parallelogram or parallelograms may be made to assume a rectangular, diamond or other shape; but during these changes the opposite sides re- 40 main parallel, and in the case of a series of parallelograms the sides of each remain parallel to the corresponding sides of each other parallelogram.

To one of the members on one side of the 45 principal pivot a lamp is attached, and to a parallel member on the other side of this pivot a counterweight is attached. The members to which the lamp and counterweight are attached may exceed in length 50 the side of the parallelogram of which each forms a part, extending beyond the point

at which it is pivoted to the adjacent side, and the lamp or counterweight may be attached to it at its junction with this adjacent side or to the extension beyond it. The 60 central pivot connects the structure to a standard, pendant rod or bracket so that the structure rotates in a vertical plane.

With such a construction the lamp may be moved in a straight line toward or away 65 from the central pivot, around which it may also be rotated vertically, without destroying its balance. As the lamp moves toward or away from the central pivot the counterweight is also brought automatically toward or away from it, and as the lamp rises the counterweight falls.

In the construction of such apparatus, one of the members of the parallelogram may have a tubular sleeve attached to it to 70 receive within it a hollow receptacle which can contain the requisite weight, say of shot, and can then be adjusted up or down through the tubular member and fixed in the requisite position.

The invention will be further and more particularly described with reference to the examples of construction shown in the accompanying drawings, in which—

Figures 1, 2, 3 and 4 each show in eleva- 85 tion an example of construction of apparatus according to this invention.

Referring to Fig. 1 of the drawings, the parallelogram structure consists of two parallel members 1 and 2 connected at their 90 ends to two other parallel members 3 and 4. In this figure the member 3 is represented as the lamp-bearing member and the lamp 8 is shown in dotted outline as attached to it at its junction with member 2 and in solid 95 outline to an extension 3^a of member 3. The counterweight 9 is consequently shown as attached in a corresponding manner to member 4, (the parallel member on the other side of the principal pivot 5) at its junction 100 with member 1 and to an extension 4^a of member 4. In this figure two secondary members 11, 12 are shown connecting the opposite sides of the parallelogram in order that the principal pivot may be central and 105 the structure symmetrical. Either of these two secondary members may however be omitted without affecting the structure, and by modifying the weight of the counterweight and the position at which it is attached to member 4 or its extension 4^a, the center of gravity may be made to pass

through the member 2 and the central pivot pass through that member as shown at Fig. 4, in which case no such secondary members are necessary. In Fig. 1, as in all the drawings, the principal pivot 5 is represented as carried by a telescopic standard 6; but it may be carried by a pendant rod or bracket. The pivot may be carried by a head 7 which itself revolves about the standard 6.

10 At Fig. 2 the structure is formed by a series of parallelograms, and two of the adjacent sides of each (13 and 14 of one parallelogram and 15 and 16 of the other) are prolonged to form a cross, and the prolongations form two of the sides of the parallelogram next to it. The members 3 and 4 as also 1 and 2 remain parallel in all their movements, as do the sides similarly numbered in Fig. 1, and to one of these the lamp 8 is attached. In this Fig. 2 the member 3 is represented as the lamp-bearing member, and the lamp 8 is shown in dotted outline as attached to it at its junction with member 2, and in solid outline to an extension 3^a of member 3. The counterweight is consequently shown as attached in a corresponding manner to member 4, (the parallel member on the other side of the principal pivot) at its junction with member 1, and to an extension 4^a of the member 4.

15 In Fig. 4 the counterweight 9 is in the form of a tubular case containing shot, and is carried in a tubular sleeve 10 fixed to the member 4 of the parallelogram, so that its axis lies parallel to the said member. The weight 9 is adjustable within the sleeve 10 in the direction of the length of the said sleeve and therefore of the member 4, and is fixed in its adjusted position by a set screw 40 10^a which passes through the said sleeve and contacts with the weight to clamp it in position.

20 In accordance with the law of the resolution of force the single weight shown in Figs. 1 and 2 may be replaced by two or more weights having an equivalent value. In Fig. 3 a construction is shown in which it is replaced by two such weights 9.

25 It will be understood that instead of the arm or member 3^a supporting the lamp extending in a straight line or coaxial with the member 3, it might be constructed at an angle thereto, and similarly the member 4^a may be constructed at an angle to the member 4, and where gas is to be conducted through the system or where electric conductors or the like are to be carried and concealed, the members of the structure may be tubular, all as will be well understood by those acquainted with the manufacture to which this invention relates.

30 What I claim as my invention and desire to secure by Letters Patent is:—

1. An adjustable support or bracket; comprising in combination a plurality of rigid

members, pivotal connections between said members to form a parallelogram structure, a support for said structure, means for pivotally connecting the said structure to the said support so that the said structure is 70 rotatable in its own plane, an article such as a lamp at one end of said structure, and means at the other end of said structure to counterbalance the weight of said lamp, substantially as set forth. 75

2. An adjustable support or bracket; comprising in combination a plurality of rigid members, pivotal connections between said members to form a parallelogram structure, a support for said structure, a pivotal connection between said structure and said support to enable said structure to be rotated and expanded and contracted in a vertical plane and also to be rotated in a direction at right angles to the plane containing the 80 said structure, an article such as a lamp at one end of said structure, and means at the other end of said structure to counterbalance the weight of said lamp, substantially as set forth. 85

3. An adjustable support or bracket; comprising in combination a plurality of rigid members, pivotal connections between said members to form a parallelogram structure, a support for said structure, a pivotal connection between said structure and said support so that said structure is rotatable in its 90 own plane, an extension to the member at one end of said structure, an article such as a lamp connected to said extension, an extension to the parallel member at the other end of said structure, and a weight secured to said extension to counterbalance the weight of said lamp, substantially as set forth. 95

4. An adjustable support or bracket; comprising in combination a plurality of rigid members, pivotal connections between said members to form a parallelogram structure, a vertical tubular support, a head rotatably carried at the upper end of said support, a horizontal pivot pin passing through said structure at right angles to the plane containing the latter and entering said head so that the said structure is rotatable in its 100 own plane, an article such as a lamp at one end of said structure, and means at the other end of said structure to counterbalance the weight of said lamp, substantially as set forth. 105

5. An adjustable support or bracket; comprising in combination a plurality of rigid members, pivotal connections between said members to form a parallelogram structure, a vertical tubular support, a head rotatably carried at the upper end of said support, a horizontal pivot pin passing through said structure at right angles to the plane containing the latter said pin entering said head and forming means upon which said 110

parallelogram structure can be rotated and expanded and contracted in the plane containing the same, an extension to the member at one end of said structure, an article 5 such as a lamp connected to said extension, an extension to the opposite and parallel member at the other end of said structure, and a weight secured to said extension to

counterbalance the weight of said lamp, substantially as set forth. 10

In witness whereof I have hereunto set my hand in the presence of two witnesses.

HENRY MACNAUGHTON MACNAUGHTON-JONES.
